AUTOMATIC CONTROL OF VARIABLE PHYSICAL CONDITIONS

Harold William Ibbott, London, England, assignor to Negretti & Zambra, London, England

Application February 9, 1943, Serial No. 475,289
In Great Britain July 1, 1942,

5 Claims. (Cl. 74—1)

This invention relates to improvements in automatic control apparatus of general application to various arts where it is desired automatically to adjust conditions, for example physical conditions such as heat or pressure, to a state which may be particularly predetermined but whose value is required to be varied according to the effect of one or more other factors, which it may be desired to take into account.

The automatic control apparatus according to the invention comprises a primary device responsive to changes in the condition to be controlled and exerting a force against resistance to its displacement which varies according to the state of said condition, mechanical linkage serving to transmit from a force-applying device resistance to said displacement, means adapted, when the force exerted by said primary device is out of balance with the resistance thereto, to vary the state of said condition in the sense of restoring balance, and at least one secondary device responsive to changes in another factor or factors required to be taken into account in the determination of the desired state of the first-mentioned condition, which latter device operates on the mechanical linkage to vary its leverage.

The secondary device or devices may be adapted to operate on the mechanical linkage without receiving or transmitting any substantial reaction from or to the force being transmitted through the linkage to or from the said force-applying device.

Preferably the mechanical linkage comprises a pivoted frame or like element about the axis of which there are opposed moments of forces, one of these forces being applied to the frame or like element through a member pivoted about an axis inclined to the axis of the frame or like element, so that the distance of the line of action of the force from the axis of the frame or like element varies when the pivoted member is rocked, and the member is adapted to be rocked through the agency of the said secondary device.

The secondary device(s) may operate on the mechanical linkage through the intermediary of means which as the response(s) of the device(s) continue in the same sense produce a non-proportional and/or eventually a reverse movement of the rocking member.

As a further or alternative means of introducing the effect of another factor, the force of the force-applying device may be adapted to be varied at will and/or automatically in accordance with a change in a factor required to be taken into account in the control. Thus the force-applying device may comprise a plurality of

springs capable of individual and several adjustments by means responsive to a change in a factor or to the will of an operator.

The invention is illustrated in the accompanying drawing which shows in perspective one form of control apparatus suitable for carrying the invention into effect.

In the drawing a diaphragm or capsule 1, responsive to pressure changes which may occur in or in relation to the operation of machinery, and which pressure may be directly or indirectly produced from any physical condition in question, is connected to a frame 2 free to rotate about a vertical axis Y—Y₁. Supported by the frame 2 is a bell crank lever 3 pivoted to rotate about a horizontal axis. A strut 4, serving to transmit an opposing force to the frame 2, bears horizontally on the side of one arm of the bell crank lever 3. This strut at its other end bears on the side of one end of another bell crank lever 5 pivoted on a second frame 6 so as to be rotatable about a horizontal axis. The second frame 6 pivots about a vertical axis Y₂—Y₃ and supports a further bell crank lever 7, at the opposite side of the frame to the bell crank lever 5 against which the said other end of the strut 4 bears, and this further bell crank lever 7 is pivoted about a horizontal axis. A second strut 8 bears at one end on the side of the bell crank lever 7 and at the other end upon a pivoted lever 9 which is directly subjected to the force of two springs 10, 11. Normally, i. e. when a state of equilibrium exists, the two first mentioned bell crank levers 5, 3 pivot on a common horizontal axis X—X₁ whilst the bell crank lever 7 pivots on an axis X₂—X₃ passing through the point of contact of the remote end of the strut 8 where it bears upon the pivoted lever 9.

An extension of the second frame 6 carries an insulated contact 12 arranged to operate between high and low electric contacts 13, 14 respectively of a reversible electric motor 15. The movement required by the insulated contact 12 to "make" from "mid-off" position is very small and the pivot points of the bell crank levers do not move sensibly from their normal axes.

When a state of equilibrium exists the force from the diaphragm or capsule 1 is in balance with the reactions of the springs 10, 11 and contact 12 is at "mid-off" position. Whilst this condition is maintained the force of the springs is confined solely to react on the diaphragm or capsule, and in no way through the bell crank levers to the means for rocking the latter, to which reference will now be made.

Each of the bell crank levers is adapted to be

rocked responsively to factors or conditions which are required to be taken into account in the control. Such factors or conditions may exert their influence through diaphragms or capsules 16, 17 connected to the bell crank levers 3, 5 and 7 directly or through linkage so as to apply the rocking force in a vertical line so that the displacement of the frames 2 and 6 on which the bell crank levers are pivoted will not react upon the secondary diaphragms or capsules.

In the arrangement shown the diaphragm or capsule 16, responsive to one secondary factor, is provided with linkage indicated generally at 18 which causes the rotation of a spindle 19 connected by links 20, 21 to the bell crank levers 3 and 5. A stop 22 limits the rotation of the spindle 19 in one direction and the rotation of the spindle in the other direction takes place against the action of a spring 23, which tends to return the spindle back to its position against the stop 22.

The diaphragm or capsule 17 which is responsive to a further secondary factor is connected by means of linkage 24 to the bell crank lever 7.

It will be understood that the words "vertical" and "horizontal" are used in the above description in a relative sense.

The effect of the rockings of the bell crank levers 3, 5 and 7 is to alter the radius of application of the forces transmitted from the springs 10, 11 to the primary diaphragm or capsule 1 by bringing the struts 4 and 8 nearer to or further away from the pivotal axes of the frames 2 and 6.

It will therefore be understood that a change in one or other of the secondary factors, as well as a change in the primary condition to be controlled, will bring about a condition of unstable equilibrium, and when this occurs the insulated contact 12 will make electrical connection to cause the electric motor 15 to operate in one direction or the other to actuate means for controlling the primary condition to which the primary diaphragm or capsule 1 is responsive.

As has already been indicated, the spring or springs may be adjusted automatically or at will so as to vary the force reacting through the linkage upon the primary diaphragm or capsule 1. This may be effected by employing the two co-axial springs 10, 11, the spring 10 having a strength which is a determined percentage of the strength of the spring 11. A cam lever 25, connected to an operative element in connection with the machinery or apparatus in which the control is being exercised, is arranged by means of a rod 26 to take off the force of the spring 10 from the lever 9 upon which it bears. Another cam lever 27 is adapted by means of a rod 28 to change the force of one or both springs from the lever 9 upon which they bear, and in this way the effect of the control apparatus may be modified on demand.

The control apparatus according to the present invention is particularly suitable for regulat-

ing the temperature of internal combustion engines, particularly of aircraft, by controlling the amount of cooling air used, applying the differential pressure set up by the passage of cooling air to operate the primary diaphragm or capsule, and imposing upon the control the effects of other variable factors required to affect the regulator to control the temperature of the engine, such as boost pressure, cooling air temperature, altitude, supercharger gear and pilot's will.

I claim:

1. Automatic control apparatus comprising a primary device responsive to changes in the condition to be controlled and exerting a force against resistance to its displacement which varies according to the state of said condition, mechanical linkage serving to transmit from a force-applying device resistance to said displacement, means adapted, when the force exerted by said primary device is out of balance with the resistance thereto, to vary the state of said condition in the sense of restoring balance, and at least one secondary device responsive to changes in another factor or factors required to be taken into account in the determination of the desired state of the first-mentioned condition, which latter device operates on the mechanical linkage to vary its leverage, said mechanical linkage comprising a pivoted frame about the axis of which there are opposed moments of forces, a member to apply one of these forces to the frame, said member being pivoted about an axis inclined at approximately right angles to the axis of the frame so that the distance of the line of action of the force from the axis of the frame varies when the pivoted member is rocked, the said forces being exerted by the said primary device and said force-applying device, and the said pivotal member being rocked through the agency of the said secondary device.

2. Automatic control apparatus as claimed in claim 1 in which means are provided for varying the strength of the force applied by the force-applying device.

3. Automatic control apparatus as claimed in claim 1 in which means are provided for automatically varying the strength of the force applied by the force-applying device in accordance with a change in a factor required to be taken into account in the control.

4. Automatic control apparatus as claimed in claim 1 in which the force-applying device comprises a plurality of springs capable of individual and several adjustments.

5. An automatic control apparatus as claimed in claim 1, in which the said secondary device operates upon said pivoted member so that as its response continues in the same sense it produces a non-proportional movement of the said pivoted member.

HAROLD WILLIAM IBBOTT.
